UNITED STATES PATENT OFFICE

JOHN E. SPALDING, OF NEW HAVEN, CONNECTICUT

SCREEN FOR PROJECTED PICTURES

Application filed July 14, 1930. Serial No. 467,693.

This invention relates to improvement in screens, either translucent or opaque, such as are used for projecting pictures, etc. These screens are usually mounted in a frame and secured thereto by lacings, but it is somewhat difficult to lace the screen evenly in the frame, and tension on the screen varies with atmospheric conditions. In some cases, the frame forms a part of the cabinet.

10 The object of this invention is to mount the screen in a frame, so that it will be firmly and evenly held in position and adapted to adjust itself to various atmospheric conditions, and the invention consists in a screen for projected pictures having certain details of construction as will be hereinafter described and particularly recited in the claims.

In the accompanying drawings:

20 Fig. 1 is a front view of a screen for projected pictures constructed in accordance with my invention;

Fig. 2 is an edge view of the same;

Fig. 3 is a view with the flaps of the frame open;

25 Fig. 4 is a sectional view on the line 4—4 of Fig. 1;

Fig. 5 is a face view of a modified form of frame; and

Fig. 6 is an edge view of the same.

30 In carrying out my invention I employ a rectangular frame 10 of suitable size, the corners of which are mortised or doweled together. The screen 11 is formed from suitable fabric material and usually provided with a fabric binder 12 to which hooks 13 are attached. Secured to the frame itself by screws 14 or otherwise are coil-springs 15, the ends of which engage with the hooks 13. The position of the fixed end of the springs is at an angle to the connecting-hooks on the screen, so that these springs stand in an inclined position, and pull in opposite directions toward opposite edges of the screen.

Preferably, the inner edge of the frame will be formed with a recess 16 in which the springs are located, and secured to each side of the frame are flaps 17 formed with recesses 18 corresponding to the recesses 16, so that when the flaps are turned inward they will hide and protect the springs, although, for

many purposes, there is no objection to the exposure of the springs.

This construction permits the ready mounting or demounting of the screen and owing to the reverse draft of the springs on each side 55 the tension upon it is even; and the springs compensate for varying changes of atmosphere, so as to maintain the screen in a smooth condition.

Such screens are used in display cabinets 60 and for projecting pictures.

I claim:

1. A screen for projected pictures consisting of a frame and a screen, and springs connected with the frame and with the edge of 65 the screen, the springs on each side of the screen being arranged at different inclinations so as to oppose each other.

2. A screen for projected pictures comprising a frame formed with a groove extending 70 around the inner edge, springs mounted on the frame in said groove and those on each side extending at different inclinations to oppose each other, a screen provided with hooks adapted to be engaged by the said springs, 75 and grooved flaps secured to the casing and adapted to fold over and enclose said springs.

In testimony whereof, I have signed this specification.
